TABLE MARBLE GAME

Fritz W. Falck, Los Angeles, Calif.

Application September 26, 1936, Serial No. 102,648

4 Claims. (Cl. 273—121)

My present invention relates to a table marble or ball game.

One of the principal objects of this invention is to provide a structure of this class embodied in a racing or competitive game which may be played by one person.

Another important object of this invention is the provision of a novel combination of means for selection of a particular field, class, color, or the like, and means for making certain plays or goals corresponding with each of the latter, and also means for registering such plays or goals.

A further object of this invention is the provision of novel means of recording a score or goal and of compounding the score.

A still further important object is to provide novel means of registering all plays or goals of a particular nature irrespective of the selection.

Still another object is the provision of such means which will permit an unlimited number of plays until the game is concluded by a predetermined number of plays or score of a particular nature.

Also, an important object is the provision of means which will automatically shut off or control the mechanism, when the game is finished or won, so that no more balls may be obtained, or no more plays registered.

A further object of this invention is the provision of a game structure of this class which is relatively simple, economical and durable of construction, and foolproof and positive in operation.

With these and other objects in view, as will appear hereinafter, I have devised a game structure of this class having certain novel features of construction, combination, and arrangement of parts and portions as will be hereinafter described in detail and particularly set forth in the appended claims, reference being had to the accompanying drawings and to the characters of reference thereon which form a part of this application, in which:

Fig. 1 is a top view of my table marble game in a preferred form, showing particularly the game board;

Fig. 2 is a wiring diagram of the game, showing only the essential elements thereof; and,

Fig. 3 is an enlarged fragmentary sectional elevation of my game, taken through 3—3 of Fig. 1.

My game structure, illustrated in the drawings, is built in table form and has at its upper side a game board inclined downwardly towards the front of the board, and comprises a lower

and for convenience a selector field 11 and a playing field 21. On the board, and preferably at one side, is a registering means 31.

At one side of the game board, preferably opposite the registering means, is an alley or channel 2 for directing game members to the main or playing field 21, and having a lateral branch 2^a for directing a game member to the selector field 11. The game members, herein referred to, are balls 3 which are received from below the board 1 and projected into the alley or its branch by a spring actuated plunger 4. At the juncture of the main alley or channel 2 and its branch 2^a is a gate 5, pivoted on the spindle 5^a, which is operated by mechanism presently to be described, and which, when extended angularly across the main channel, as shown by dotted lines in Fig. 1, will direct a ball into the selector field, and will then be closed over the branch channel 2^a, as will be hereinafter described.

At the lower portion of the board comprising the selector field are a plurality of holes 12, 13, 14 and 15, the portions around these holes being differently characterized, such as by blue, yellow, green, or red colors. The first ball played will be the selector ball, and is propelled into the angularly directed branch channel 2^a, which will be open, and is then directed toward the top of the selector field. By any means now commonly employed, the ball is directed and deflected from place to place until it finds a pocket in which one of the holes 12, 13, 14 or 15 is located. The dropping of the ball in one of these holes actuates a switch 59, and by suitable electric means, releases a cam or rocker 52 and closes or allows to be closed the gate 5, as will be described more specifically hereafter.

The upper portion of the board, comprising the main or playing field 21, is provided with a plurality of series 22, 23, 24 and 25 of holes or goals, the holes or goals in each series being designated a, b, and c. Thus the goals in series 22 are designated 22^a, 22^b, and 22^c.

The upper end of the channel 2 merges into an upper curved end 21^a of the playing field for directing the ball on to the field. The playing field 21 has a multiplicity of different devices 26, 27, 28, and 29, and the like, as now commonly employed, for directing and deflecting the balls by various circuitous and zig-zag routes toward and into the several pockets, holes, or goals.

The registering means illustrated consists of a number of fore and aft, or inclined rows of frosted glass covered illuminated chambers, herein referred to as registering lights or registering

devices. There is provided one row of registering lights for each of the holes 12, 13, 14 and 15, and for the corresponding series of goals 22, 23, 24, and 25 in the playing field. These rows are 5 designated 32, 33, 34, and 35, each row, as illustrated, consisting of eight lights, those in row 32 being designated 32^a, 32^b, 32^c, 32^d, 32^e, 32^f, 32^g, 32^h. The lower lights in each row, namely 32^a, 33^a, 34^a, and 35^a correspond to the holes 12, 13, 10 14 and 15, and when the first ball played drops into one of said holes the corresponding light is lighted, thereby visually registering the class or color selected.

The electrical hook-up is so arranged that the 15 projection of a ball into any of the holes in each series on the main field 21 is registered by the lights in the corresponding series or row of lights in the registering means. The mechanism is further so arranged that the different holes in 20 the different series have different values; that is, in the specific structure shown, a ball dropping into one of the lowermost holes 22^a, 23^a, etc., of each series will illuminate only one light in the corresponding series in the registering means; 25 balls dropping into the holes 22^b, 23^b, etc., will consecutively light two lights in the corresponding series of the registering means; and balls dropping into holes 22^c, 23^c, etc., will consecutively light three lights in the corresponding series 30 of the registering means. The value of each hole or goal is preferably indicated, as shown. Only one light in each series of the registering means remains lighted. This shows at a glance on the registering means, the value or score in each 35 series of goals or holes 22, 23, 24 or 25.

The game is successfully completed or won if all the lights in the same row, corresponding to the illuminated selector light 32^a, 33^a, 34^a, or 35^a, have been lighted. That is, when a selector light 40 is illuminated, the object of the succeeding plays is to light all the lights in the same row.

At the upper end of the playing field is a hole 41 which registers on a counter 42 the odds which are conceded or paid to the player upon successful completion or winning of a game. The odds are increased by balls dropping into hole 41.

The several mechanisms for controlling registering means 31, counter 42, and other apparatus of my game, by the dropping of balls into the 50 several pockets or holes referred to above, is best illustrated in the wiring diagram of Fig. 2, and may be best disclosed by describing in detail the several parts of the game together with the operation of the mechanisms.

55 I employ preferably two sources of electricity, the one designated 46 representing a battery for actuating the relays, and the like, and the other designated 47 being a generator for illuminating the signal lights.

60 The switch 48, which may be considered the main switch, is closed by a coin in any manner commonly employed. This switch may be said to shuffle or prepare the apparatus for playing a new game. This switch energizes a starting coil 49, 65 through the circuits 50 and 51, drawing its armature 49^a and rotating the cams 52, 53, and 54 which are then held in their shifted or rotated positions by dogs in the form of armatures 52^a, 53^a, and 54^a respectively. The armature 49^a is 70 immediately returned to its inoperative position, but, by reason of the particular sliding rod connection with the cams 52, 53, and 54, the cams remain in their shifted positions.

The cam 53 operates a multiple switch 55 for 75 so connecting the battery 46 to the coils 52^b, 53^b,

and 54^b, respectively for the armatures 52^a, 53^a, and 54^a, that they are ready to be energized, as will be hereinafter described. This cam 53 also connects lights in the registering means so as to illuminate the same when a ball drops into any 5 of the holes 22, 23, 24, or 25. As soon as the cams 52, 53, and 54 are rotated, the circuit of the coil 49 is broken by the switch 56 which is actuated by the cam 54.

The cam 52 is mounted on the spindle 5^a in 10 such a manner that when the coil 49 is energized cam 52 is rotated and the gate 5 shifted to its dotted line position in Fig. 1 and so held by the armature 52^a.

A gate 57 which is opened by a cam 53 (mentioned hereinafter, the connection not being shown) allows a ball 3 to be carried by a member or plunger 58 so as to roll in front of the spring actuated plunger 4, by which the ball may be projected to the playing field as stated. As the 20 ball is projected, the gate 5 deflects the ball into the lateral branch 2^a of the alley from which it rolls by gravity into one of the holes 12, 13, 14, and 15. At the underside of the game board, immediately below each hole, is a multiple finger 25 switch 59 which is closed by the dropping of the ball thereon, the ball being retained on the switch by retractable fingers 60. These fingers are operatively connected (the means not being shown), with the mechanism which forces the new coin 30 into operative position for playing a new game, so that the ball in one of the holes drops or is discharged only when the coin mechanism is operated for forcing a new coin into operative position; and when the ball drops into one of the 35 holes 12, 13, 14, or 15, it is held therein, closing the switch 59, until a new game is begun.

The dropping of a ball into one of the above holes performs two functions, namely, it shifts the gate 5, to the solid line or closed position 40 (shown in Fig. 1), and illuminates one of the "selection" lights 32^a, 33^a, 34^a, or 35^a in the registering means, that is, the light corresponding to the selection hole into which the ball has dropped. The first function is performed by energizing the coil 52^b which attracts the armature and permits the cam and the gate 5 to be rotated by a spring 52^c. The latter function is performed by connecting the particular signal light to the generator circuit. 50

The circuit to the coil 52^b is broken when the gate is closed, by opening a switch 61 to the coil. The switches 59 consist of resilient fingers which spring into non-contacting positions when the ball is released mechanically by the retaining fingers 60. When the ball is released, or permitted to drop, when starting a new game, as described above, the gate 5 is also shifted to the dotted line position in Fig. 1.

When the gate 5 is closed, as shown by solid 60 lines, the subsequent balls are projected through the main portion of the alley or channel onto the main playing field 21, and each drops into one of the holes in any of the series 22, 23, 24, or 25 and illuminates the light or lights in the corresponding series or row of the registering means. Such result is effected by the following mechanism:

Below each of the latter holes is a spring 70 switch, the switches below the holes in each series being designated 69^a, 69^b, and 69^c. The switches for each series are arranged in a trough or channel 78 which is preferably inclined downwardly from the uppermost holes to the lowermost, for example, from hole 22^c to 22^a. Thus when a ball 75

drops into any of the holes 22^a, 23^a, 24^a, or 25^a, it rolls down the channel and engages or operates only switch 69^a in the particular channel, while a ball dropping into any of the holes 22^b, 23^b, 24^b, or 25^b, will roll down the channel and operate switches 69^a and 69^b in such channel. In like manner a ball dropping into any of the holes 22^c, 23^c, 24^c, or 25^c, will roll down the channel and operate all three switches in such channel. All of the aforementioned switches for each series of holes are connected to a counter coil 71 which, when energized, shifts an armature 71^a which is operatively connected to the contact arm of a multiple contact counter switch, there being one 15 of such multiple switches for each series of holes and the corresponding row of lights in the registering means, these switches being designated 72, 73, 74, and 75. Said multiple contact counter switches 72, 73, 74, and 75 are connected respectively to the lights in the rows 32, 33, 34, and 35. Each counter switch is provided with as many stationary contacts as there are signal lights in each row of the registering means, excepting that there is provided an additional light in each row 25 which is used as a selection light. The stationary contacts in the counter switch 72 are designated 72^b, 72^c, 72^d, 72^e, 72^f, and 72^h, and are connected respectively to the lights 32^b, 32^c, 32^d, 32^e, 32^f, 32^g, and 32^h in the row 32.

30 In this instance, it is assumed that the ball is dropped into the yellow selection hole 13, as shown in Fig. 1. The playing or operation of the remaining part of the game is briefly as follows:

Balls are projected to the playing field 21 and 35 they drop singly and consecutively into any of the various holes 41, 22^a, 22^b, 22^c, 23^a, 23^b, etc. A ball dropping any time, before the game is completed, into the hole 41, will raise the odds by 40 operating the counter 42. Assuming that the balls have dropped into the various holes so that the lights 32^g, 33^g, 34^f, and 35^f of the registering device are illuminated, as shown in Fig. 1, and then the next ball drops into either of the holes 24^b or 24^c, the lights in the row 34 will pass to 34^h, 45 that is, light 34^f will be extinguished, 34^g will be illuminated and extinguished, and then 34^h will be illuminated. The illumination of any of the lights in the lower transverse row, consisting of 32^h, 33^h, 34^h, and 35^h, indicates completion of the 50 game.

On each of the multiple contact counter switches is an additional or eighth contact 72ⁱ, 73ⁱ, 74ⁱ and 75ⁱ which may be in radial alignment with the contacts 72^h, 73^h, 74^h, and 75^h so that when 55 one of the latter contacts is engaged by the respective rotating contact arms 72^a, 73^a, 74^a, or 75^a the corresponding contact 72ⁱ, 73ⁱ, 74ⁱ, or 75ⁱ, will also be contacted.

The circuit completed by any of the latter contacts will energize the coil 54^b which will attract its armature 54^a, close the switch 76, complete the circuit through the line 77, energize the coil 53^b, attract its armature 53^a, allow the cam 53 to be returned to its normal position by the spring 53^c 60 and break the connection made by the multiple switch 55, thus deenergizing the magnetic circuit. The cam 53, when returning to its normal position will close the ball feeding gate 51, that is, stop the supply of more balls when the game is 65 finished.

70 The lights of the registering means will remain lighted, until manually shut off, or by any

other means desired (not shown). When the light circuit is shut off the multiple contact counter switches are returned to their initial positions; or this may be done by the starting coil 49 when the game is started, or, as commonly referred to, "when the game is shuffled" to begin anew. Such mechanism being of conventional construction, it is not here shown.

Though I have shown and described a particular construction, combination, and arrangement 10 of parts, portions, and elements, I do not wish to be limited to the same, but desire to include in the scope of my invention the construction, combination and arrangement substantially as set forth in the appended claims. 15

I claim:

1. In a game of the class described, a field of play having a plurality of series of goals, a plurality of series of registering means, one series for each series of goals, each series of registering 20 means comprising a plurality of consecutively arranged and operated signalling devices so connected to the goals in the corresponding series of goals as to register consecutively the making of a goal in the latter series, means for feeding and 25 directing game members to said field of play, and means in operative association with the latter means and each of the series of registering means for rendering said latter means inoperative when all of the signalling devices in one series of the 30 latter are operated.

2. In a game of the class described, a field of play having a plurality of series of goals, a plurality of series of registering means, one series for each series of goals, each series of registering 35 means comprising a plurality of consecutively arranged and operated signalling devices so connected to the goals in the corresponding series of goals as to register consecutively the making of a goal in the latter series, a source of electric 40 energy for actuating said signalling devices, and switch means in operative connection with the last of the consecutively arranged signalling devices of each series for disconnecting said electric current when the last of the signalling devices 45 of any series is operated.

3. In a game of the class described, a field of play having a series of goals, a series of registering devices so connected to the goals as to operate the registering devices consecutively upon the 50 making of goals in said series, means for feeding and directing game members to said field of play so they may make said goals, and means in operative association with the latter means and said registering devices for rendering said latter 55 means inoperative when all of the registering devices are operated.

4. In a game of the class described, a field of play having a plurality of series of goals, a plurality of series of registering devices, each series 60 cooperating with a series of goals and so connected to the goals as to operate the registering devices consecutively upon the making of goals in said series, means for feeding and directing game members to said field of play so they may 65 make said goals, and means in operative association with the latter means and said registering devices for rendering said latter means inoperative when all of the registering devices of one series thereof are operated. 70
